UNITED STATES PATENT OFFICE.

WILLIAM J. DUNN AND HENRY B. TAYLOR, OF MONTREAL, QUEBEC, CANADA, ASSIGNEES TO STANDARD MACHINES LIMITED, OF MONTREAL, QUEBEC, CANADA.

WALL-PAPER-HANGING DEVICE.

1,046,452.

Specification of Letters Patent.

Patented Dec. 10, 1912.

Application filed October 8, 1910. Serial No. 585,021.

To all whom it may concern:

Be it known that we, WILLIAM J. DUNN and HENRY B. TAYLOR, both of the city of Montreal, in the Province of Quebec and 5 Dominion of Canada, have invented certain new and useful Improvements in Wall-Paper-Hanging Devices, of which the following is a full, clear, and exact description.

This invention relates to improvements in 10 wall paper hanging devices and the object is to provide a simple and inexpensive machine which will quickly and easily hang, accurately trim and paste the paper.

A further object is to provide a device 15 which will hold the trimmed and pasted paper conveniently for matching the pattern of the paper already hung, and which will cut the paper transversely when the pattern has been matched.

20 A still further object is to provide means for cutting the paper to any width when working around door, windows, etc.

Another object is to provide a machine of 25 this character which may be quickly and easily adjusted to any height of room or any standard width of paper, and which may be operated from the floor.

To accomplish these objects, we provide 30 an extensible support, adapted to stand on the floor, having at the top thereof a paper handling device driven by a suitable belt from a pulley conveniently located on the support. The paper handling device comprises a paper roll support, a pair of 35 feeding rolls having trimmers on the ends thereof, a paste reservoir containing a revolving drum over which the paper passes, and finally a pair of discharge rollers. A manually controlled cutter is 40 provided outside the discharge rolls for severing the trimmed and pasted paper after the same is adjusted to position on the wall.

In the drawings which illustrate our invention—and throughout all the figures of 45 which similar numerals refer to corresponding parts:—Figure 1 is a general side elevation of the device in operation. Fig. 2 is an enlarged side elevation of the paper handling device. Fig. 3 is a vertical section of the paper handling device, on the line 10—11 of Fig. 4. Fig. 4 is a plan view 50 of the paper handling device. Fig. 5 is a front elevation of the same, partly in sec-

tion. Fig. 6 is a front elevation of the feed 55 rolls showing the trimmers. Fig. 7 is a front elevation of the adjustable cutters in operative relation. Fig. 8 is a fragmentary section on the line 12—13 of Fig. 2, and shows the method of suspending the paste reservoir. Fig. 9 is an enlarged detail view of the support extending device.

In the drawings, 14 designates the base upon which the machine stands, 15 the lower tubular members of the support, and 16 the upper members of the support which telescope within the lower members and are preferably solid. A small housing 17 is fixed near the top of each of the tubular members 15, and each contains a gear 18 which meshes with teeth 19 formed on the members 16 so that the said members constitute reciprocatable racks. A crank 20 is provided for rotating the gears to raise the rack members 16, and small pawls 21 to hold the gears against rotation are provided in the housings 17.

Mounted on the upper ends of the racks 16, are a pair of similar side plates 22 connected at the back by rods 23 to form the framework of the paper handling device. At the front of the framework, a loose paper supporting spindle 24 is mounted in the L-shaped slots 25, so as to be readily removable for the insertion of a fresh roll 26 of paper. The space between the plates 22 is sufficient to allow the insertion of the widest standard paper used but, in case it is desired to use narrower paper, a small guide plate 27, such as shown in dotted lines 90 in Fig. 5, may be placed on the spindle 24 to keep the short roll in proper position. Above and behind the spindle 24, is a revoluble shaft 28 on which is mounted an adjustable paper guide 29, which may be 95 shifted along the shaft according to the width of paper used. The shaft 28 itself forms a guide over which the paper passes to the feed rolls 30 and 30^a, arranged one above the other. On each end of these 100 rolls the trimmers are mounted, each trimmer comprising a frusto-conical roller 31 fixed to the upper or drive roll 30, and a grooved roll 32 on the lower roll 30^a, co-operating with the frusto-conical roller to 105 form shears which trim off the margins of the paper and leave the edges perfectly smooth and parallel in order that the paper

may be hung with the edges abutting, rather than lapped over, in conformity with the best modern practice. The trimmers on one end of the feed rolls are fixed as to position, while those on the opposite ends are adjustable to accord with varying widths of margin or varying widths of paper. In order to render the adjustment possible, the body of the roll ends a considerable distance from the side plate 22 so that the trimmers may be readily shifted on the roll spindles 33. The upper trimmer is locked to the spindle by a set screw 34, while the lower trimmer is loose on the spindle but is held in engagement with the upper one by a light helical spring 35 compressed between itself and the end of the roll. This arrangement is best shown in Figs. 4 and 6.

20 The pasting device consists of a paste reservoir 36 containing a large partially submerged roller 37 which is made hollow and open at the ends so as to leave the maximum of space for the paste. This roller is mounted on a shaft 38. The ends 39 of the paste reservoir extend upwardly to the top of the side plates 22 and are hooked over the same so as to support the paste reservoir, the turned over portions being seated in depressions 39 in the plates 22. The shaft 38 is mounted in bearings 40 seated in slots in the ends of the reservoir and plates 22. These bearings are flanged inside and out, as shown best in Fig. 4, and are accurately fitted so as to prevent leakage from the reservoir. The front edge of the reservoir is provided at the ends with recessed lugs 41 adapted to support a shaft 42 carrying the paste scraper 43. The scraper 43 is in the form of a plate which is approximately balanced across the shaft 42, the rear edge thereof extending into contact with the roller 37 and the front edge lying adjacent the feed rolls 30 and 30^a, so as to form a table to guide the paper when the same is being inserted in the machine. The front portion 44 of each end of the scraper is turned around the shaft 42 to hold the scraper in place. At each end of the 45 scraper is a rearwardly projecting lug 45 which engages the ends of the paste roller 37 and scrapes the paste therefrom so that surplus paste will not be deposited on the edges of the paper where it would squeeze 50 through the joint when the paper is pressed against the wall. The amount of paste supplied by the roll 37 is regulated by the scraper, which may be raised or lowered by turning the finger nuts 46. These nuts 46 are 55 grooved to engage pins 47 projecting from the ends of the reservoir and are thereby held against reciprocation, so that by turning the nuts, the threaded rods 48, pivotally attached to the scraper on which the nuts 60 are mounted, will be moved vertically to ad-

just the scraper. The rods 48 are pivotally attached to the scraper in order that they may be easily swung inwardly to disengage the nuts from the pins 47 and allow the scraper and shaft 42 to be readily lifted 70 from the lugs 41 for cleaning, or for the removal of the roller 37. By first removing the heavy idler roll 49 which is mounted in slots 50 in the reservoir ends and plates 22, the entire pasting device, comprising the 75 reservoir, paste roller and scraper, may be lifted out of the machine in one operation and without in any way disturbing the paper in the machine. This feature is of great convenience for cleaning or filling the 80 device while in operation, and also greatly facilitates the changing of paste rollers and scrapers when a different width of paper is to be used. This changing of the paste roller for different widths of paper is necessary as the roller must be of such length as to deliver paste to within, say, $\frac{1}{2}$ of an inch of the trimmed edge of the paper to allow for expansion of the paste when the paper is pressed against the wall. If the paste 85 roller is larger, the paste is delivered to the very edge of the paper and, if it does not immediately flow over the edge of the paper, it will do so when the paper is hung and thus mar the finished work. Each length 90 of paste roller requires a corresponding scraper in order to keep the ends of the roller free from paste. To overcome the necessity of having different rollers for different widths of paper, the roller 37 is provided with one or more removable sections 95 37^a, which may be slipped off the shaft 38 and thus shorten the roller for use with narrow paper.

100 A guide plate 51 is fixed between the plates 22 in front of the feed rolls and serves to guide the paper between the rolls when the machine is being prepared for use.

Between the guide plate 51 and the shaft 28, a pair of shafts 52 and 52^a are journaled 110 one above the other, in the plates 22, and each carries an adjustable cutter, which cutters coöperate to cut the paper to any width when working around doors and windows, or in corners. The cutter 53 on the upper graduated shaft 52 is adjustable to any point on the shaft where it may be locked by means of a set screw 54, while the cutter 55, on the lower shaft 52^a, is loose on the shaft and is held in engagement with the 115 upper cutter by means of a helical spring 56 which is compressed between itself and an adjustable collar 57, secured at any point on the lower shaft by a set screw 58.

120 Adjacent the front of the machine and well above the paper roll 26, are a pair of discharge rolls mounted one above the other between the plates 22. The lower of these rolls 59 is continuous throughout its entire length while the upper roll is formed of a 130

plurality of short rollers or wheels 60 spaced well apart on the shaft 61. These rollers 60 engage the pasted surface of the paper and therefore the contact surface is made as small as possible so as to displace as little of the paste as possible. A plate 62 is secured between the end plates 22 to guide the papers between the discharge rolls.

At the extreme front of the machine and 10 in a horizontal line with the contacting surfaces of the discharge rolls, is a horizontal cutting table 63 having a longitudinal slot 64 therein. This table projects beyond the front of the device, as clearly shown in the 15 drawings, in order to allow the body of the machine some clearance from the wall. Above the table 63 is a housing 65, which projects considerably beyond the end plates 22. Within the housing is a small carriage 20 66 having a cutting wheel 67 journaled in the lower portion thereof and adapted to operate with one edge of the table slot 64, to form shears for cutting the paper transversely. The slot 64 also acts as a guide or 25 track for the carriage, which is held in close contact therewith by means of a semi-elliptical spring 68 mounted within the top of the housing 65 and engaged by rollers 69 on the top of the carriage. The shifting of the 30 carriage is accomplished by means of cords or chains 70, of equal length, attached to each end thereof and passing out of the ends of the housing over rollers 71. These cords depend a suitable distance and are provided 35 at the ends with weighted balls or handles 72. Since the cords 70 are of equal length, one handle will be higher than the other when the carriage is at the end of its travel, and the operator will, therefore, be enabled 40 to tell at a glance which cord to pull in order to draw the carriage across the device to sever the paper.

The rotation of the various rolls and cutters is effected by any suitable gearing operated from a convenient point, such as the 45 belt gearing shown in the drawings. It is, however, obvious that chain or wheel gearing, or a combination of the two, may be substituted. A large drive pulley 73 is 50 mounted on an adjustable bracket 74 on the lower member 15 of the support, and is provided with a suitable handle 75. This pulley is connected by a belt 76 with a pulley 77 on the shaft of the upper feed roll 30. 55 Mounted on the same shaft as the pulley 77, are two other pulleys 78. From one of the pulleys 78, a crossed belt 79 runs to the pulley 80 on the drive shaft 38 of the paste roller 37, while from the other pulley 78 a 60 belt 81 runs to the pulley 82 on the shaft 61 of the upper discharge roll. This belt also passes over and drives the pulley 83 on the upper shaft 52 of the adjustable cutters.

All the feed rolls are preferably of rubber 65 mounted on metal cores or shafts. All the

cutting devices comprise two coöperating members which act like shears and, therefore, preclude any possibility of tearing the paper. Only one member of each pair of rolls or cutters is positively driven, the other 70 member revolving by frictional contact with the driven member or moving paper.

In setting up the machine, the paste reservoir is first filled and the scraper adjusted according to the thickness of paste 75 used. The paper roll 26 is then placed on the spindle 24 and inserted in the machine and the paper passed over the shaft 28, between the shafts 52 and 52^a, over the guide 51 and between the feed rolls 30 and 30^a. 80 The roll 49 is preferably removed and the paper drawn back over the paste roller 37 and the roll 49 replaced over the paper. The paper is then drawn forward and passed over the guide 62 between the discharge rolls 59 and 60, and over the cutting table. If, in the latter part of this operation the paper is drawn through the machine, it will be coated with paste as it passes over the roller 37, so that there will 90 be only a very small amount of waste caused by unpasted paper. This waste portion may be trimmed off if desired by pulling the higher of the two handles 72, so as to draw the carriage 66 across the paper, the cutting wheel 67 therein coöperating with the table slot 64 to form shears which sever the paper and at the same time cut the ends at exactly right angles with the side edges thereof. The device is now moved up to the 100 wall 84 to be papered and the support extended by turning the crank 20 until the paper handling device is raised to the correct height. The correct height may be ascertained by measuring the distance from 105 the picture molding 85, cornice or ceiling to the top of the cutting table, which distance should equal the distance from the front edge of the table to the cutting slot, in order that when the paper lying horizontally on the table is severed and swung 110 to a vertical position, it will exactly reach the picture molding 85. When the machine has been set as to height, the bracket 74 carrying the drive pulley 73 is adjusted to 115 properly tension the belt 76. The driving pulley is now rotated to operate the paper handling mechanism which delivers the trimmed and pasted paper, the paper being damp and heavy with paste does not curl 120 but falls in a vertical line from the edge of the cutting table. When the lower end of the paper strip reaches the skirt board 86, or chair molding if there is one on the wall, the rotation of the driving pulley is stopped 125 and the paper pressed against the wall sufficiently to hold the same in place by means of the usual long handled brush. The operator then pulls the higher handle 72 and draws the transverse cutter across the paper 130

to sever the same. The machine is moved to one side and the paper pressed into place in the usual manner. The next length of paper is lowered in the same way until the pattern on the two strips matches, and is then severed at the top as before. When a door, window or corner, is reached, the adjustable cutters 53 and 55 are adjusted on their shafts 52 and 52^a to cut a strip of paper the required width. In setting the cutters 53 and 55, the distance is measured from the stationary end trimmers 31 and 32, the cutters being set as shown in Fig. 7. Otherwise the operation is the same. As the paper passes between the feed rolls 30 and 30^a, it also passes between the trimmers mounted on the ends of these rolls and the edges trimmed perfectly smooth and parallel by the overlapping cutting edges of the cutters, as will be easily understood by an inspection of Figs. 5 and 7. The roller 37 revolves through the paste in the reservoir 36 and raises a constant fresh supply therefrom, the amount of which is gaged by the scraper 43 before it is deposited on the paper passing over the roller. Wall paper is always rolled with the face or pattern side in and it will be obvious from Fig. 3, that by taking the paper from the back of the roll 26, as shown, the reverse side will be in contact with the paste roller. By doubling the paper around the roll 49, it is discharged over the edge of the cutting table with the pasted side away from the machine and toward the wall, so that after the paper roll is once inserted in the machine, it need not be touched by the operator's hands at all, thus eliminating any danger of soiling. The trimming from the edges of the paper will pass down through the space at the ends of the scraper formed by turning the portions 44 thereof around the shaft, and may be readily removed from time to time.

The most desirable way of changing the paste roller and scraper to accommodate different widths of paper, is to form the paste roller with a removable end portion 37^a, which may be slipped on or off the shaft 38 when a different width of paper is used. As the scraper cannot be conveniently made in sections, a small bar 45^a is adjustably mounted thereon so that it may be slipped out to scrape the end of the roll when the portion 37^a thereof is removed, as indicated in Fig. 4.

Having thus described our invention, what we claim is:—

1. A paper hanging machine comprising telescoping supports, means for vertically adjusting the supports, a paper pasting and trimming device mounted at the top of said supports, a device on the lower portion of one of the supports for operating the pasting and trimming device, and means for adjust-

ing said operating device to maintain the same a constant distance from the paper pasting and trimming device.

2. A paper hanging machine comprising a telescoping support having toothed upper members, pinions cooperating with said upper members to vertically adjust the same, a paper trimming and pasting device mounted at the top of said support, and means for operating the trimming and pasting device adjustably mounted on the lower members of the support. 70

3. A paper hanging machine comprising a vertically adjustable support having tubular lower members and toothed upper members 80 slidable within the lower members, pinions adjacent the top of the lower members meshing with the upper members, locking pawls for said pinions, a paper trimming and pasting device mounted at the top of the 85 upper members of said support, and operating mechanism for said trimming and pasting device slidably mounted on the lower members of the support to maintain a constant distance from said trimming and pasting device. 90

4. A paper hanging machine comprising a telescoping support, rack and pinion mechanism for vertically adjusting said support, a paper carrying device mounted at the top 95 of said support containing paper edge trimming knives, a paper pasting device, a transverse paper cutting knife, and an auxiliary paper cutting device.

5. In a paper hanging machine, a suitable support, a paper carrier at the top thereof, means for vertically adjusting the paper carrier, a pasting device in said paper carrier comprising a paste trough, a sectional roller partially submerged therein, an 100 adjustable face scraper for the roller, an adjustable end scraper mounted on the face scraper, paper edge trimming knives, and a transverse paper cutting knife. 105

6. In a paper hanging machine, a suitable support, a paper carrier at the top thereof, means for vertically adjusting said paper carrier, a pasting device therein comprising a paste trough and a sectional paste roller, paper edge trimming and transverse paper 110 cutting knives in said paper carrier, and a paper guide adjustable to aline the paper with the paste roller. 115

7. A paper hanging machine comprising tubular supports, a paper carrying device 120 having toothed legs slideable in said supports, pinions adjacent the top of the supports cooperating with the legs to vertically adjust the paper carrying device, said paper carrying device comprising a paper pasting device, means for regulating the amount of paste delivered by said pasting device, paper edge trimming knives, a transverse paper cutting knife, and auxiliary paper cutting knives. 125

8. In a wall paper hanging machine vertically adjustable supports, a frame mounted on said supports, containing a paper carrying spindle, feed rolls, paper edge trimming knives, a paper pasting device, a transverse paper cutting knife, and an auxiliary paper trimming device.

9. In a wall paper hanging machine, a suitable support, a vertically adjustable paper carrying device, mounted on said supports, paper edge trimming knives, a paper end cutting means and a paper pasting

means in said carrying device, means for regulating the amount of paste delivered by said pasting means, and auxiliary paper cutting knives adjustable to divide the trimmed paper longitudinally. 15

In witness whereof we have hereunto set our hands in the presence of two witnesses.
